UNITED STATES PATENT OFFICE.

MORRIS B. SOLOMON, OF BROOKLYN, NEW YORK.

TRAY STRUCTURE.

Application filed June 11, 1924. Serial No. 719,276.

To all whom it may concern:

Be it known that I, MORRIS B. SOLOMON, a citizen of the United States, and a resident of Brooklyn, in the county of Kings and State of New York, have invented certain new and useful Improvements in Tray Structures, of which the following is a specification.

This invention relates to tray structures such for instance as is illustrated in Patent No. 1,094,261 of April 21, 1914, and has for its primary object to provide simple, novel and inexpensive means for covering the tray frame with ornamental sheet metal and permanently securing said sheet metal covering in close contact with the surfaces of said frame.

It is another object of the invention to provide an improved frame structure for trays having means whereby a glass bottom plate and an ornamental picture may be easily, quickly and securely assembled in connection therewith.

It is a further general object of the invention to provide such improvements in frame structures of this character as will provide a very substantial and durable connection between the side and end members of the frame, and at the same time materially reduce manufacturing cost.

With the above and other objects in view, the invention consists in the improved tray frame structure as will be hereinafter more fully described, illustrated in the accompanying drawings and subsequently incorporated in the subjoined claims.

In the drawing wherein I have illustrated several simple and practical embodiments of my invention and in which similar reference characters designate corresponding parts throughout the several views:

Figure 1 is a fragmentary top plan view of a tray frame constructed in accordance with one embodiment of my invention;

Figure 2 is a detail fragmentary perspective view of the longitudinal and side members of the frame showing the same separated and having the ornamental metal covering sheet applied thereto;

Figure 3 is a vertical sectional view taken on the line 3-3 of Figure 1;

Figure 4 is a horizontal sectional view through a corner of the frame taken on the line 4-4 of Figure 3;

Figure 5 is a fragmentary perspective view showing a slightly modified form of

the sheet metal covering plates on the angularly extending frame members;

Figure 6 is a detail side elevation showing one means for securing the sheet metal plates to the frame;

Figure 7 is a similar view showing an alternative securing means for said plates;

Figures 8, 9 and 10 are detail sectional views of the invention as applied to different forms of the frame members; and

Figure 11 is a plan view of a corner section of a frame in which the ends of the angularly extending members are mitered and showing another method of connecting the frame members and securing the sheet metal plates thereto.

Referring first to Figures 1 to 4 of the drawing, the frame structure which may be of any suitable size or shape, consists of a plurality of rails or members preferably of wood. As herein shown, I have disclosed my invention in connection with two of the frame members designated 5 and 6 respectively, which extend at right angles to each other. Each frame member which as shown in this embodiment, is of general rectangular shape in cross-section, is provided in its lower portion and at its inner side with a rabbet 7 having an undercut wall providing an inclined face 8 extending upwardly from the inner face of the frame member.

The inner and outer and top and bottom surfaces of the frame member are covered by a sheet metal plate 9 bent into the cross-sectional form of said frame member, said sheet metal covering extending over the inner face of the frame member having a longitudinal flange 9' projecting upwardly into the rabbet 7 and closely contacting with the inclined face 8 of the undercut wall of said rabbet. As illustrated in Figure 2 of the drawings, the sheet metal covering 9 on the frame member 5 has all of its parts terminating at the same point with relation to the ends of said frame member, while the sheet metal covering on the other frame member 6 has its outer side portion, the top portion and the bottom portion thereof extended beyond the end face of said frame member and the inner side portion and the angular flange 9 on said covering sheet as indicated at 10. When the frame members are assembled, these projecting parts 10 of the covering on the rail 6 extend over the metal covering sheet on the other frame member 5. Thus as seen in Figure 4, the projecting

part 10 of the outer portion of the metal covering on frame member 6 laps over upon the end edges of the parts of the metal covering on the frame member 5 as well as the 5 end of said frame member. The top portion of the covering on the frame member 6 extends over the projecting portion of the metal covering on the member 5, while the projecting bottom portion of the metal covering on the 10 member 6 laps over or extends upon the bottom portion of the covering on the frame member 5. Thus it will be understood that the sheet metal covering at the corners of the frame completely encloses all parts of 15 the wood frame members so that the latter are invisible.

The bottom of the tray consists of a glass plate 11, the marginal edges of which project into the rabbets 7 of the several frame 20 members, the said bottom plate bearing upon the metal covering sheets at the juncture of the flanges 9 thereof with the inner portions of said metal sheets, as shown in Figure 3 of the drawings. On the opposite side of 25 the glass bottom plate, an ornamental lithograph or picture, as indicated at 12, is arranged and over the latter the sheet metal plate 13 is disposed. The marginal edges of 30 this sheet metal plate extends between the bottom faces of the several frame members and the bottom portions or flanges of the metal covering sheets 9 thereon. After the frame members with the bottom plate and the parts 35 12 and 13 have thus been assembled, the nail 14 of an ornamental rosette 15 is driven through the overlapping top portions of the sheet metal cover plates 9 and into the frame member 5. A second nail shown at 16 is also driven through the overlapping bottom portions of the metal covering sheets and through the marginal edge of the sheet metal plate 13 into said frame member. In this 40 manner, it will be apparent that the frame member with the ornamental metal covering sheet and the several other parts of the tray are securely held in assembled relation against relative movement. Such a structure is very durable and substantial and will 45 withstand abusive handling without separation of the frame parts. It also permits of 50 the very rapid assemblage of the several elements with a minimum of manual labor.

In Figure 5 of the drawings I have shown a slightly different form of the end of the metal covering sheet on the frame member 5 in which the outer portion thereof is provided with an extension 17 projecting beyond the end edges of the other portions of 55 said covering sheets and is adapted to be turned inwardly over the end face of the member 5 between the same and the projecting portion 10 of the sheet metal covering on the other frame member 6. This inwardly turned flange reinforces the structure 60 and gives a more finished appearance

to the corners of the sheet metal covering. In Figure 6 I have illustrated this latter construction with a securing means similar to that shown in Figure 3 of the drawing. However, in Figure 7, I have shown a single securing or fastening nail 18 in lieu of the two separate nails 14 and 16. In this case, the nail 18 extends entirely through one of the frame members and the overlapping top and bottom portions of the metal 70 covering sheets thereon.

In Figure 8 of the drawings I show my invention as applied to a slightly different form of the frame members in which each frame member has its inner face obliquely 75 inclined inwardly and downwardly from its upper edge as at 19. The metal covering sheet 9' is bent to conform to this cross-sectional shape of the frame member, and instead of providing the upwardly and outwardly inclined surface 8 as above described, the frame member is formed at the lower edge of its inner face 19 with a relatively narrow horizontal surface 20 over which the metal sheet extends. The glass 80 bottom plate and the ornamental picture are applied in the same manner as heretofore described and at suitable intervals, nails 16' 85 are driven through the inwardly extending bottom portion of the covering sheet 9' 95 and the metal retaining sheet 13' into the wood frame members.

In Figure 9 the members of the tray frame are illustrated as having a curved or convex inner face 22 over which the metal covering 100 sheet extends, the inner portion of said covering sheet being bent to provide the angular flange 23 which extends over the surface of the rabbit in the frame member which receives the glass bottom plate. The 105 edges of the bottom plate bearing against this flange will effectually preclude any separation of the metal covering sheet from the inner curved face of the frame member. In this instance, the metal covering and the 110 tray bottom are secured and fixed in assembled relation in the same manner as shown in Figure 8.

In Figure 10 I have shown a relatively narrow frame member having the vertical 115 inwardly and downwardly inclined inner face 19', and the undercut wall of the rabbit having the inclined surface 8'. In such construction, the tray bottom and the covering sheet for the frame are also secured in 120 assembled position in the same manner as shown in Figure 8.

In Figure 11 I show the angularly disposed tray members of Figs. 8, 9 or 10, 125 having a mitered joint at the corners of the tray as at 24, the outer side portion of the covering sheet on one of said members being turned inwardly between the corresponding portions of the covering sheet on the other frame member and the face of said member, 130

as indicated at 25. In this instance, the securing handle 26 is driven through the covering sheet on the latter frame member through the inward extension 25 of the covering sheet on the other frame member and into both of the wood frame members, thereby closely holding the mitered face of the frame member in contact with each other.

10 From the foregoing description considered in connection with the accompanying drawing, the construction and several advantages of the various embodiments of the invention herein described will be fully understood.

15 While I have illustrated certain examples of a tray frame structure embodying my improvements, it is possible that other analogous arrangements might be devised incorporating the same novel features therein 20 whereby the essential considerations of strength and rigidity, with ease of assembly and low cost of manufacture may be attained.

It will, therefore, be understood that while 25 I have selected certain structures as best illustrating my present improvements, the novel features thereof are susceptible of embodiment in various other alternative forms, and I therefore, reserve the privilege of resorting to all such legitimate changes in the 30 form, construction and relative arrangement of the various parts as may be fairly embodied within the spirit and scope of the invention as claimed.

35 I claim:

1. A tray structure comprising a frame consisting of members adapted to be arranged in angular relation to each other with the ends of one abutting the sides of 40 the other adjacent to its end and each having a rabbet in its inner face provided with an undercut wall, a sheet metal covering for each of said frame members having an angularly disposed flange at one edge en-

gaged upon said undercut wall of the rabbet, the metal covering sheet of one frame member having an end portion extending longitudinally beyond the end of the frame member for engagement in an overlapping relation with a part of the metal covering sheet of the adjacent angularly extending frame member, a tray bottom having its marginal edges engaged in said rabbets and seated upon the flanges on said metal covering sheets, a retaining plate for said tray bottom engaged upon the lower edges of the frame members, and means for securing said covering sheets and the retaining plate to the frame members.

2. A frame structure for trays and the like, comprising frame members adapted to be arranged in angular relation to each other with the end of one abutting the side of the other adjacent to its end and each having a rabbet to receive the marginal edge of the tray bottom, a sheet metal covering for each of said frame members covering three sides and a part of the fourth side of each of said members and provided with an angularly disposed flange extending into said rabbet for engagement with one wall thereof, the sheet metal covering on one of said frame members having its top, bottom and outer side extended and projecting longitudinally beyond the end of said frame member and engaging in an overlapping relation with the end and the top and bottom of the sheet metal covering of the adjacent frame member when said members are arranged in angular relation to each other, and a fastening nail extending through said engaged parts of the sheet metal coverings and securing the same to one of said frame members.

In testimony that I claim the foregoing as my invention I have signed my name hereto.

MORRIS B. SOLOMON.
